UNITED STATES PATENT OFFICE

2,036,426

IRONING ELEMENT

Andrew O. McCollum, Detroit, Mich., assignor to
 Hydraulic Brake Company, Detroit, Mich., a
 corporation of California

Original application March 1, 1934, Serial No.
 713,596. Divided and this application January
 17, 1935, Serial No. 2,287

5 Claims. (Cl. 68—9)

This invention relates to ironing machines, and more particularly to an ironing element.

An object of the invention is to provide an ironing element of the type generally known in the art as a buck, including a relatively light pressed-steel plate deformed so as to lend strength and rigidity thereto.

Another object of the invention is to provide an ironing buck including a corrugated steel plate having a continuous groove adjacent its perimeter in direct communication with the respective channels formed in the face of the plate by the corrugations.

Another object of the invention is to provide an ironing buck including a steel plate deformed to lend strength and rigidity thereto and to collect condensate.

A further object of the invention is to provide an ironing buck including a plate deformed to lend strength and rigidity thereto and to collect condensate, and to provide a peripheral flange extending above and below the plate to more effectively support an ironing pad and to provide means for securing a cover for the pad.

Other objects of the invention will appear from the following description taken in connection with the drawing which forms a part of this specification, and in which,—

Fig. 1 is a top plan view of a buck, partly broken away.

Fig. 2 is a longitudinal sectional view of the buck, substantially on line 2—2, Fig. 1;

Fig. 3 is a cross-sectional view substantially on line 3—3, Fig. 1; and

Fig. 4 is a fragmentary view substantially on line 4—4, Fig. 1.

Referring to the drawing for more specific details of the invention, 10 represents a plate, the profile of which is preferably semi-elliptical. The plate has a convex surface or face provided with transverse corrugations 12. These corrugations lend strength and rigidity to the plate, and channels 14 formed in the face of the plate by the corrugations provide suitable means for the reception of condensate present during prolonged ironing operations. The periphery of the plate is deformed to provide a continuous groove 16 in direct communication with the respective channels 14 and a peripheral flange 18 extending above the corrugations 12 and below the back of the plate, the purpose of which will hereinafter appear.

Secured on the back of the plate 10 are bearing plates 20 for the engagement of power actuating means, not shown, and clips 22 are stamped from

the bearing plates for the attachment of springs 24. These springs resiliently support the plate 10. Troughs 26 secured on the back of the plate 10 communicate with the continuous grooves 16 as by way of openings 28. These troughs receive 5 the condensate collected in the channels 14 and the continuous groove 16 and convey such condensate as may be collected to a suitable receptacle, not shown. The troughs have lateral flanges 30 flapped against the bearing plates 20 10 and secured against displacement as by rivets formed on the corresponding ends of pins 32 adaptable for cooperation with suitable guides, not shown.

A perforated plate 34 is supported on the corrugations 12, and suitably secured against displacement. The periphery of the plate 34 overhangs the continuous groove 16, and the upper surface of the face of the plate 34 is flush with the upper edge of the flange 18 on the plate 10. 20 The purpose of the plate 34 is to provide a relatively smooth surface interrupted only by the perforations provided for the passage of condensate. A felt pad 36 is spread over the perforated plate, and a fabric cover 38 spread over the pad 25 has a draw string 40 made fast back of the lower edge of the flange 18 on the plate 10.

This application is a division of my co-pending application Serial No. 713,596, filed March 1, 1934, and is made in accordance with the requirements 30 of the United States Patent Office under the provision of Rule 42.

Although the invention has been described in connection with certain specific embodiments, the principles involved are susceptible of numerous other applications that will readily occur to persons skilled in the art. The invention is, therefore, to be limited only as indicated by the scope of the appended claims.

Having thus described the various features 40 of the invention, what I claim is new and desire to secure by Letters Patent is:—

1. An ironing element comprising a corrugated plate having a peripheral flange extending upward from the plate and a groove in the upper 45 face of the plate adjacent the flange.

2. An ironing element comprising a corrugated plate having a peripheral flange extending upward from the plate and a groove in the upper 50 face of the plate adjacent the flange, and a perforated plate supported on the corrugations.

3. An ironing element comprising a transversely corrugated plate having a peripheral flange extending above the upper face of the plate and a groove in the face of the plate adjacent the 55

flange, and a perforated plate supported on the corrugations having its margin extending over the groove.

4. An ironing element comprising a transversely corrugated plate having a peripheral flange extending above and below the plate and a groove in the upper face of the plate adjacent to the flange, a perforated plate supported on the corrugations having its margin extending over the groove, and troughs on the back of the plate communicating with the groove.

5. An ironing element comprising a transversely corrugated plate having a peripheral flange

extending above and below the plate and a continuous groove in the upper face of the plate adjacent the flange, a perforated plate supported on the corrugations having its margin extending over the groove, the face of the perforated plate being in the same plane as the upper edge of the flange, a felt pad on the perforated plate extending over the upper edge of the flange, and a cover over the pad having its fastening means secured beneath the lower edge of the flange.

ANDREW O. McCOLLUM.
